(57) **CLAIM**

An ornamental design for a magnetic buckle, as shown and described.

DESCRIPTION

FIG. 1 is a perspective view of one embodiment of a first buckle clasped with a second buckle of the magnetic buckle; FIG. 2 is a top plan view thereof;

FIG. 3 is a side elevation view of thereof, the opposing side being a mirror image;

FIG. 4 is a first end view of the first buckle, the first end view of the second buckle being a mirror image thereof;

FIG. 5 is a bottom plan view of the first buckle and the second buckle;

FIG. 6 is a perspective view of the magnetic buckle with the first buckle unclasped from the second buckle;

FIG. 7 is a second end view of the first buckle; and,

FIG. 8 is a second end view of the second buckle.
